(57) **CLAIM**

The ornamental design for a vehicle screen set, as shown and described.

DESCRIPTION

FIG. 1 is a front elevational view of a vehicle screen set.

1 Claim, 2 Drawing Sheets

FIG. 2 is a front elevational view of the upper left screen of FIG. 1, the upper right screen being a mirror image of the upper left screen.

FIG. 3 is a side elevation view of the upper left screen.

FIG. 4 is a top plan view of the upper left screen, the bottom view being substantially a mirror image of the top view shown.

FIG. 5 is a front elevational view of the lower left screen of FIG. 1.

FIG. 6 is a side elevational view of the lower left screen.

FIG. 7 is a top plan view of the lower left screen, the bottom view being substantially a mirror image of the top view shown.

FIG. 8 is a front elevational view of the lower right screen of FIG. 1.

FIG. 9 is a side elevational view of the lower right screen; and,

FIG. 10 is a top plan view of the lower right screen, the bottom view being substantially a mirror image of the top plan view shown.

The broken lines shown in FIG. 1 are for illustrative purposes only and form no part of the claimed design.
